R. J. DICKIE.
COIN CHUTE FOR COIN OPERATED MACHINES.
APPLICATION FILED JAN. 5, 1917.

Patented July 24, 1917.

Robert James Dickie,
by:- B. Anger,atty.

UNITED STATES PATENT OFFICE.

ROBERT JAMES DICKIE, OF KELBURN, NEW ZEALAND.

COIN-CHUTE FOR COIN-OPERATED MACHINES.

1,234,300.

Specification of Letters Patent. Patented July 24, 1917.

Application filed January 5, 1917. Serial No. 140,784.

To all whom it may concern:

Be it known that I, ROBERT JAMES DICKIE, a subject of the King of Great Britain, residing at Kelburn, Wellington, New Zealand, have invented a new and useful Improved Coin-Chute for Coin-Operated Machines; and I do hereby declare the following to be a full, clear, and exact description of the same.

This invention has been devised in order to provide an improved construction of coin chute for the introduction of coins into coin operated machines of all classes.

The new construction is designed to prevent the entry of damaged or distorted coins into the mechanism of the machine and thereby to save any liability of a machine becoming choked by a distorted or damaged coin lodging within the coin chute. With the present invention provision is made for the automatic rejection of any such coins and also for the rejection of coins of a smaller size from the coin chute at a point before it reaches the mechanism. The construction however is such as to allow a coin of proper size and with a uniform diameter and edge to pass freely into the machine.

To this end the invention consists broadly in constructing the first portion of the chute with a bottom designed to swing out as each coin is introduced into the upper end of the chute and then to swing back to its normal position, and in making the chute of a height such that only a coin of the size for which it is designed and of uniform roundness will pass down it while coins of similar size but with distorted edges will be gripped and held between its top and bottom. When a distorted coin is held in the chute, the next coin by swinging out the bottom will release such distorted coin and allow it to fall away from the chute. The chute is also arranged at an incline toward the side opposite to that upon which the bottom swings so that any smaller coin on introduction into the chute will fall out of its open side.

In describing the invention reference will be made to the accompanying sheet of drawings, in which:—

Figure 1 is an upper side elevation of the coin chute.

Fig. 2 is a back end elevation thereof.

Fig. 3 is a lower side elevation, and

Fig. 4 a front end elevation thereof.

Fig. 5 is a cross sectional elevation looking from the back end of the chute.

Fig. 6 is a detail view illustrating means for the accurate adjustment of the height of the coin's passage in the chute.

In carrying out the invention, the chute is formed by a fixed portion 7 constituting the lower side and top of the chute and made integral with or firmly attached to a front plate 8 having the coin entry slot 9 made therein. This fixed portion is arranged at an incline from front to rear and also with a side inclination from its bottom edge, up and out. The coin slot 9 is also made with a corresponding side inclination.

The upper edge of the fixed portion is made of such cross sectional shape as to form a channel 10 (Figs. 4 and 5) which extends the full length of the chute.

The other portion of the chute is formed by a swinging member 11 which is attached at its ends to arms 12 and 13 which arms are swung on a hinge rod 14 carried along the top of the fixed portion 7. This swinging member thus, by gravity, will fall and rest on the upper face of the fixed portion and, to aid such action, it may be suitably weighted, as at 15 (Figs. 1 and 2). Its lower edge is arranged to register with the lower edge of the fixed portion and is made of such cross sectional shape as to form an inwardly extending ledge 16 and an outer edge 17. This ledge and edge together with the face 18 of the fixed member 7 against which the ledge engages, form a groove 30, down which a coin on its edge may roll. The groove extends to near the back of the plate 8 and beneath the bottom end of the coin slot 9 so that a coin inserted through the slot will run into the groove. A passage for the coin inserted in the slot is thus provided through the chute, the coin resting upon and rolling down the groove 30 and being held at its upper edge in the groove 10.

Attached to the arm 12 is a cam 19 which extends inwardly therefrom across the back face of the plate 8 and the lower end of the coin slot 9. This cam is so shaped that it will be in the path of the proper coin entering the slot but will be pushed to one side when pressure is exerted on the coin to insert it in the slot and allow the coin to enter and then to pass over the cam and to

free it. This side push of the cam will cause the member 11 to swing out on its pivot so that the ledge 16 will move away from the face 18 of the fixed member, as shown by the dotted lines in Fig. 5.

5 The face of the lower or rigid member is cut away throughout most of its length with the exception of the top groove or channel 10 and the bottom face 18. The distance 10 between the lower edge of the groove 10 and the upper edge of the face 18 is so adjusted that a coin of the right size will engage and rest against these edges when it is rolling down the groove 30. Any coin 15 of smaller size will not be held at its upper edge, and consequently because of the side inclination of the chute, will topple over the lower edge and fall clear of the chute.

In order to check any coin of the right 20 denomination but of mutilated or deformed edge passing down through the chute, a number of screws 20 are screwed through the top of the fixed member 7 so as to project into the groove 10 at regular intervals apart 25 along such groove as shown particularly in Fig. 6. These screws form pegs that will be engaged by any irregularity in the coin's edge so as to stop it and hold it in the chute, their bottoms being accurately adjusted to 30 just permit of the passage between them and the bottom 16 of the groove 30 of a coin of uniform circumferential edge. Consequently when a coin has thus been checked by the screw pegs 20 and is held in the chute, 35 it will remain there until another coin is inserted through the slot 9 and the swinging member turned out, when the coin will lose the support of the ledge 16 and will drop down out of the chute.

40 In order that a coin may not pass right into the chute before the swinging member has dropped back after the coin passes across the cam 19, means are provided to engage the coin and hold it while the swinging 45 member is out and then to release it when that member closes. These means consist in a pin 22 that is made fast to a bow 23 that extends from the upper side of the swinging member 11, over the top of the chute to the 50 underside thereof. The pin is attached to this latter end of the bow and so positioned that when the member 11 is closed, the pin will not prevent the coin's passage through the chute, but when such member is swung 55 out, the pin will move in and lie at right angles across the chute so as to form a block to the coin passing through, as indicated by the dotted lines in Fig. 5. This pin 22 is made of such a length that its inner end will 60 move back clear of the coin's passage simultaneously with the closing of the chute to form the supporting groove for the coin. It is also so positioned that the coin while 65 stopped by it, will be held upon a short ledge 24 (shown in dotted lines in Figs. 1

and 3) which extends from the inside of the fixed member 7 and leads down at an incline to the top end of the ledge 16. The coin, while resting on this ledge 24, will be kept from falling out sidewise by a solid 70 portion 25 of the wall of the fixed member on the lower side, and by guards 26 (Fig. 1) fixed to the plate 8 on the upper side.

I claim:—

1. A coin chute formed by a fixed member having a groove extending along its upper edge adapted to receive the edge of a coin and provided with adjustable pegs projecting down into the groove at intervals in its length, a swinging member pivoted upon such fixed member and having a coin supporting ledge along its bottom edge, a coin slot arranged at the end of the chute, and means upon the swinging member whereby a coin passing through the coin slot will 35 cause the swinging member to turn out from the fixed member, substantially as specified.

2. A coin chute formed by a fixed member having a groove extending along its upper edge adapted to receive the upper edge of a coin and provided with adjustable pegs projecting down into the groove at intervals in its length, a swinging member pivoted upon such fixed member and normally engaging therewith and formed with a coin supporting ledge along its bottom edge, a coin slot arranged at the end of the chute, and a cam attached to the swinging member and extending across a portion of the coin slot, substantially as specified.

3. A coin chute formed by a rigid member having a groove along its upper edge adapted to receive the upper edge of a coin, a swinging member pivoted upon the rigid member and normally engaging therewith and formed with a coin supporting ledge arranged parallel with and beneath the groove in the rigid member, adjustable pegs arranged at intervals along the said groove, a coin slot at one end of the chute, a cam 1 upon the swinging member arranged to extend across a portion of the coin slot, a coin supporting ledge upon the fixed member adjacent to the said coin slot and means whereby a coin may be retained on such ledge while the swinging member is out of normal position, substantially as specified.

4. A coin chute formed by a rigid member having a groove along its upper edge adapted to receive the upper edge of a coin, a swinging member pivoted upon the rigid member and normally engaging therewith and formed with a coin supporting ledge arranged parallel with and beneath the groove in the rigid member, adjustable pegs 1 arranged at intervals along the said groove, a coin slot at one end of the chute, a cam upon the swinging member arranged to extend across a portion of the coin slot, a coin supporting ledge upon the fixed member ad-

5 jacent to the said coin slot, a curved bow attached to the swinging member and extending up over the top of the chute and down on the other side thereof and a pin fixed to the end of such bow and positioned to extend across the coin chute when the swinging member opens, substantially as specified.

In testimony whereof I have signed this specification in the presence of two sub- 10 scribing witnesses.

ROBERT JAMES DICKIE.
